UNITED STATES PATENT OFFICE.

CHARLES WHITE, OF EAST ORANGE, NEW JERSEY, ASSIGNOR TO WESTERN ELECTRIC COMPANY, INCORPORATED, OF NEW YORK, N. Y., A CORPORATION OF NEW YORK.

GENERATING SYSTEM.

1,374,266.

Specification of Letters Patent. Patented Apr. 12, 1921.

Application filed October 23, 1918. Serial No. 259,366.

To all whom it may concern:

Be it known that I, CHARLES WHITE, a citizen of the United States, residing at East Orange, in the county of Essex, State 5 of New Jersey, have invented certain new and useful Improvements in Generating Systems, of which the following is a full, clear, concise, and exact description.

This invention relates to electrical generating systems and more particularly to 10 such systems in which reserve sources of current are employed for signaling purposes.

In some telephone systems, especially 15 those which are employed for composite telephone and telegraph service, remotely controlled sources of signaling current are frequently provided. In such instances it is extremely desirable to provide an alternative or reserve source of current which automatically will be made available upon the 20 failure of the main source. In such cases it is also desirable that a suitable indication should be given, notifying the attendant of 25 the substitution of the reserve source for the main source.

It is the object of this invention to provide an improved system of this character which will be simple and inexpensive and 30 reliable in its operation.

To attain this object, in accordance with a feature of the invention, switching means is provided for automatically substituting a reserve source of current, in association 35 with a current impressing means, for a main source of current upon the improper functioning of the main source, such substitution being maintained independently of the switching means by an indicating control 40 means.

The nature of the invention will clearly appear from the following specification and the annexed drawing in which is shown, diagrammatically, one embodiment thereof as 45 applied to a remotely controlled signaling system.

In the accompanying drawing, a relay 5 and a condenser 6 are bridged across the incoming conductors 1 and 2 of a line circuit, which conductors may lead to a distant station, not shown, since it is unessential to a proper understanding of the invention, and are normally continued to conductor extensions 3 and 4 respectively, which may 50 lead to any suitable signaling device. The

relay 7 controlled by relay 5, controls relay 8 for disconnecting the extensions 3 and 4 from their normal connection with conductors 1 and 2 and for associating therewith the secondary winding either of transformer 60 15 or of transformer 16. Relay 7 also controls the operation of the buzzer or other interrupting device 9 in circuit with the primary winding of the transformer 16. Associated with buzzer 9, relays 10 and 11 65 coöperate to cause the operation of relay 18 upon the failure of buzzer 9 to operate. Relay 12, operating upon the operation of relay 18 and locking under the control of key 17, serves to maintain relay 18 under 70 the direct control of relay 7. The buzzer or other signaling device 13 associated with relay 12 and jointly controlled by key 17 serves to continuously indicate the operated condition of relay 12. 75

It is thought that the invention will be more fully comprehended from the following description of the operation of the system shown.

Upon the receipt of an incoming call, signaling current impressed upon the line conductors 1 and 2 at the distant station, flows through relay 5 and condenser 6, causing the operation of relay 5. Relay 7 operates over a circuit established from battery 80 through the winding of relay 7 and the contact of relay 5 to ground. Relay 8 is also operated over a circuit established from battery, through the winding of relay 8 and the contact of relay 7 to ground. The operation of 85 relay 8 removes line conductor extensions 3 and 4 from their normal association with line conductors 1 and 2 respectively, and connects with such extensions through the normal contacts of relay 18 and the alternate contacts of relay 8, the secondary winding of transformer 16. A circuit is also established from battery, through the contact and winding of buzzer 9, the primary winding of the transformer 16, the windings of relays 11 and 10 in series, the middle normal contact of relay 12 and the contact of relay 7 to ground. Relay 10 and buzzer 9 operate over this circuit but due to an insufficient amount of current flowing under such 90 conditions through such circuit, if buzzer 9 is operating in a proper manner, relay 11 does not operate. Thus, the alternating current induced in the secondary winding of transformer 16, by the interrupted current 100 105 110

flowing through the primary winding of such transformer, flows through the normal contacts of relay 18 and the alternate contacts of relay 8 to the conductors 3 and 4, 5 and causes the operation of any suitable signaling device which may be associated with such conductors. Upon the cessation of signaling current on the line, relays 5, 7 and 8 release, removing the secondary of transformer 16 from its association with the extensions 3 and 4, and reestablishing these extensions in their normal association with line conductors 1 and 2 respectively.

In case buzzer 9 fails to operate in such 15 a circuit the uninterrupted current flowing through relay 11 under such conditions is sufficient to cause the operation thereof, whereupon relay 18 operates over a circuit established from battery through the winding of relay 18, the left-hand normal contact of relay 12, the alternate contact of relay 11, the alternate contact of relay 10, the middle normal contact of relay 12, and the contact of relay 7 to ground. By opening 20 its normal contacts relay 18 removes the secondary winding of transformer 16 from its association with the line conductor extensions 3 and 4, and by closing its right-hand and middle alternate contacts, it connects the 25 secondary winding of transformer 15 with such extensions in a similar manner. The closure of the left-hand alternate contact of relay 18 causes the operation of relay 12 over a circuit established from battery through 30 the winding and the right-hand normal contact of relay 12, the contact of relay 18 and the contact of relay 7 to ground. Buzzer 14 is operated over a circuit from battery through the contact and winding of buzzer 40 14, the primary winding of transformer 15, the left-hand alternate contact of relay 18 and the contact of relay 7 to ground. The alternating current thereupon induced in the secondary winding of transformer 15 45 due to the interrupted current in the primary winding of such transformer flows through the right-hand and middle alternate contacts of relay 18 and the alternate contacts of relay 8 to the line conductor extensions 3 and 4 for operating the signaling device associated with such extensions. Relay 12 locks in an operated condition over 50 a circuit established from battery, through the winding and the right-hand alternate contact of relay 12 and the contact of key 17 to ground. Signaling buzzer 13 is also continuously operated over a circuit established from battery through the contact and winding of buzzer 13, the right-hand alternate contact of relay 12 and the contact of key 17 to ground. The audible signal produced by buzzer 13 serves to indicate the substitution of the reserve source of signaling current associated with the transformer 60 15 instead of the main source associated with

transformer 16 due to the improper functioning of the buzzer 9. The attendant in response to the signal produced by buzzer 13 may readjust buzzer 9 for proper operation and when such adjustment has been secured 70 actuate key 17, thereby releasing relay 12 to cause the cessation of the signal produced by buzzer 13 and to remove relay 18 from the control of relay 7. However, as long as key 17 is unactuated, although relays 5, 7 and 8 release as before, and relay 18 releases, upon the removal of signaling current from the conductors 1 and 2, the winding of relay 18 is maintained in association with the contact of relay 7 due to the locking of relay 12. 80 Thus upon a subsequent application of signaling current to the line conductors 1 and 2, thereby causing the re-operation of relays 5, 7, 8 and 18 signaling current flows from the secondary winding of transformer 15 85 over the conductors 3 and 4. Also in case key 17 is actuated, before buzzer 9 is readjusted and after signaling current has been removed from conductors 1 and 2, although buzzer 13 ceases to operate, relay 12 releases 90 and relay 18 is removed from the direct control of relay 7, nevertheless a subsequent application of signaling current will cause the sequence of operations previously described as occurring upon the improper functioning 95 of buzzer 9, insuring that the current induced in the secondary of transformer 15 flows over the conductors 3 and 4.

In case the contact of buzzer 9 fails to close thus removing the battery supply from the circuit including relays 10 and 11 thereby releasing such relays, relay 18 operates over a circuit extending from battery through the winding of relay 18, the left-hand normal contact of relay 12, the normal contact of relay 10, the middle normal contact of relay 12 and the contact of relay 7 to ground. The other operations thereupon occur, as previously described in connection with the operation of relay 18.

It will be evident that by means of this invention, not only is the reserve source of current automatically brought into service by an indicating switching means upon the improper functioning of the main source 115 but also such reserve source is maintained available for service under independently controlled means, thereby insuring that the main source will not be brought into service until it is in condition to function properly.

What is claimed is:

1. In a generating system, a transmission line circuit, a plurality of sources of current, one of said sources being normally disconnected from the line, switching means for connecting said source to the line, means controlled thereby to prevent the connection to the line of the said source during the improper function thereof and to connect an 130

other source to the line, and means for maintaining such other source in association with the line.

2. In a generating system, a transmission line circuit, a source of current normally disconnected from the line, switching means for connecting said source to the line, another source of current, means controlled by said switching means to prevent the association of the first mentioned source therewith during the improper functioning of the source and to associate the other source therewith, and independently controlled means for maintaining such other source under the control of the switching means.

3. In a generating system, a transmission line circuit, a source of current adapted for association therewith, controlling means associated with the line for connecting such source with the line, another source of current, switching means controlled by the inoperative condition of the first mentioned source for removing such source from the control of the first mentioned means and for placing the other source under the control of such means, independently controlled means for maintaining such other source under the control of the first mentioned means, and a signaling device controlled thereby.

4. In a generating system, a transmission line circuit, a relay associated therewith and responsive to current thereon, a source of current comprising a battery, an interrupter and a transformer, switching means controlled by the relay for connecting the source

with the line, a second source of current, a marginal relay associated with the first mentioned source of current and operating upon the failure of operation of the interrupter, switching means controlled by the marginal relay for removing the first mentioned source from the control of the relay and to place the second mentioned source under control of such relay, an independently locking relay operated by the second mentioned switching means for maintaining the second source of current under such control, and a signaling device controlled by the locking relay.

5. In a generating system, a transmission line circuit, a relay associated therewith and responsive to current thereon, an interrupter, a source of current, a second relay controlled by the first mentioned relay for associating the interrupter and the source of current with the line, a marginal relay included in circuit with the interrupter and operating upon the failure of the interrupter to operate, a second source of current, a switching relay controlled by the marginal relay for removing the interrupter and the first mentioned source of current from the line and for connecting the second mentioned source of current to the line, a locking relay for controlling the switching means, a signaling device controlled thereby, and a control key for the locking relay.

In witness whereof, I hereunto subscribe my name this 18th day of October, A. D., 1918.

CHARLES WHITE.
